UNITED STATES PATENT OFFICE.

BURT D. STEVENS, OF EVANSTON, ILLINOIS, ASSIGNOR TO MIEHLE PRINTING PRESS
& MANUFACTURING CO., OF CHICAGO, ILLINOIS, A CORPORATION OF ILLINOIS.

BRAKING MECHANISM.

Application filed March 26, 1923. Serial No. 627,570.

To all whom it may concern:

Be it known that I, BURT D. STEVENS, a citizen of the United States, residing at Evanston, in the county of Cook and State 5 of Illinois, have invented certain new and useful Improvements in Braking Mechanism, of which the following is a specification.

This invention relates to printing press 10 control mechanism and more particularly to power transmission and brake mechanism for printing presses. It is an improvement over the arrangement disclosed in the application Serial No. 526,764, filed by Edward 15 Cheshire, on January 3, 1922.

One object of the invention is to provide simple, durable and efficient brake mechanism for a printing press whereby the operation 20 of the press may be quickly interrupted and the moving parts thereof stopped.

Another object is to provide a belt drive 25 between the motor driven shaft and the main shaft of the printing press whereby the tautness may be properly maintained under all 30 operating conditions.

Another object is to provide a power 35 transmission system for printing presses in which the parts are accessible to facilitate any changes or repairs and which at the same time are protected to prevent injury 40 to the operator.

Another object is to provide driving and 45 brake mechanism for a printing press adapted to meet all of the requirements for successful commercial use.

These and other objects are accomplished 50 by means of the arrangement disclosed on the accompanying sheets of drawings, in which—

Figure 1 is a fragmentary side elevation of 55 a vertical type of printing press embodying my invention;

Figure 2 is a fragmentary enlarged side 60 elevation of the same press;

Figure 3 is a fragmentary end elevation 65 of the arrangement shown in Figure 2; and

Figure 4 is a fragmentary detail plan 70 view of a motor drive pulley and associated parts shown at the extreme left hand side of 75 Figure 2.

The various novel features of the invention 80 will be apparent from the following description and drawing and will be particularly pointed out in the appended claims.

Referring to the figures of the drawings, 85

it will be noted that my invention is illustrated in connection with a vertical type of printing press including a base frame 10, supporting a way frame 11, in which a type bed, not shown, is vertically reciprocated. 60 The type bed cooperates with a cylinder 12 having a rotating movement and also, in this instance, having a vertically reciprocating movement.

The main shaft 13 from which the various 65 parts of the press are driven, is provided with a pulley 14 which is driven by a belt 15 receiving its motion from a driving pulley 16 and passing around idler pulleys 17 and 18 to be referred to more in detail herein- 70 after.

The driving pulley 16 is mounted upon 75 one end of a motor driven shaft 19 which rotates in a bearing 20 formed in one part of a bracket 21, secured to the press frame 10. A bearing cap 22 completes the bearing 20 and includes an integrally formed arm 23 carrying a pin 24 upon which a combined belt and pulley retainer and guard 25 is pivotally mounted. Not only does this 80 guard 25 cover the top of the pulley 16 and the associated portion of the belt 15, but said guard includes an inner side plate 26 and an outer side plate 27, which not only 85 act as a safety guard for the operator, but the outer plate 27 also serves the function of retaining the belt 15 on the pulley 16 and retaining the pulley on the shaft 19. No other 90 means is provided for preventing endwise removal of the pulley 16 from the motor drive shaft 19. Accordingly, it is a very simple matter to withdraw the driven pulley 16 from the shaft 19 and apply the same or another pulley to said shaft if it is desired 95 to vary the speed at which the press is to be operated. It is simply necessary to swing the guard 25 upwardly and pull outwardly upon the pulley 16, it being assumed, of course, that the belt 15 previously has been 100 slackened.

The tautness of the driving belt is controlled by the main hand operated lever 28 which is pivotally mounted upon a stud 29 passing through a side plate 30 and into the bed frame 10 of the press. This lever 28 105 has mounted thereon the idler pulley 17 which cooperates with the idler pulley 18, the latter of which is pivotally mounted upon a pin 31 carried in the upper end of an arm 32 pivotally mounted upon a stud 33, 110

- threaded into the main frame 10 of the press. The arm 32 has a forwardly extending projection 34 which is operatively connected to a spring pressed rod 35, having a spring 36 coiled therearound and operating in a manner to yieldably press the idler pulley 18 to the left as viewed in Figures 1 and 2. From the arrangement thus far described it will be appreciated that when the main operating hand lever 28 is swung to the right from the position shown in Figure 1, to the position shown in Figure 2, that the idler pulley 17 will follow for thrusting the belt 15 into engagement with the other idler pulley 18, the degree of tautness of the belt being controlled by the final position which the lever 28 is given and the action of the spring 36 upon the idler pulley 18. In this connection, the lever 28 carries a detent 37 which is adapted to engage the teeth 38 of a segment 39 forming a part of a bell crank lever pivotally supported at the point 40. By means of the tooth segment 39 which controls the adjusted position of the idler pulley 17, and the spring 36 which operates upon the other idler pulley 18, the degree of tautness of the belt 15 is controlled, and any inaccurate positioning of the idler pulley 17 will be compensated for by the spring 36 operating upon the other idler pulley 18.
- As mentioned above, the tooth segment 39 forms a part of the bell crank lever and more particularly forms part of one arm 41 of the bell crank lever 42 having its other arm 43 vertically arranged and normally held by a locking member 44 in the form of a bell crank lever pivotally supported at the point 45. The vertical arm 46 of this bell crank lever has pivotally connected thereto a weighted dog 47, the counter-clockwise rotation of which is limited by a pin 48 carried on the vertical arm 46. Under certain predetermined conditions in the operation of the press, the weighted dog 47 is engaged by an extended plunger member 49 during a vertical movement of the latter, with the result that the arm 43 of the bell crank lever 42 is released from the locking member 44, causing said bell crank lever 42 to rotate in a counterclockwise direction upon its pivot point 40 as viewed in Figures 1 and 2, thereby releasing the detent 37 and the main hand operated lever 28 which, under the tension of the driving belt 15, are swung to the left on the pivot point 29. As a result thereof no further driving power is transmitted from the driving pulley 16 to the main shaft 13 of the press.
- Heretofore the operating parts of the press have been permitted to continue to move through their regular cycle until said parts, as a result of friction, have come to a state of rest. However, said continued movement of the operating parts of the

press, after the driving connection no longer is effective, causes a waste of considerable time. Accordingly, I have provided means for not only slackening the belt, but for stopping the operation of the press almost instantaneously. This means takes the form of a cam operated brake. In this connection, a brake shoe 50 is provided to co-operate with a fly wheel 51 mounted upon the main press shaft 13, the brake shoe being carried by a brake head mounted upon a pin 52 carried in one end of a lever 53, suitably supported by a pin 54. One end of the lever 53, namely, the left hand end, as shown in Figures 1 and 2, is provided with an inclined surface or cam 55 which cooperates with the lower end of an arm 56 integrally formed with the main hand operated control lever 28 and pivoted upon the stud 29. The cam lever 53 is limited in its counterclockwise rotation about the pin 54 by a suitably supported adjustably mounted set screw 57.

With respect to the operation of the brake, it will be understood that when the detent 37 is released from toothed segment 39 either as a result of the manual operation or automatic operation, the main lever 28 will rotate about its pivotal support 29 in a counterclockwise direction as shown in Figures 1 and 2, not only to slacken the belt 15 and thereby render ineffective the driving connection between the driving pulley 16 and the main shaft pulley 14, but also to cause the lower end of the projection 56 to pass into engagement with and move upwardly upon the cam 55 to thrust the brake shoe 50 into engagement with the fly wheel 51 for causing the operating parts of the press to come to substantially an immediate stop. The cooperative action of the projection 56 and cam 55 intensifies the braking action. In this way the operating parts of the printing press may be efficiently stopped and a great deal of time saved thereby. To release the brake, it is merely necessary to swing the hand operated lever 28 in a clockwise direction, as viewed in Figures 1 and 2, until the projection 56 moves out of engagement with the cam 55, thereby releasing the brake head and permitting it to lower out of engagement with the fly wheel 51 by gravity action.

It is my intention to cover all modifications of the invention falling within the spirit and scope of the following claims.

I claim:

1. In a printing press, the combination of a press operating shaft, a driving shaft, a power transmitting belt therebetween, a plurality of idler pulleys for controlling the tautness of said belt, an operating lever carrying one of said pulleys and controlling the operation of the press, and press braking means controlled by said lever.

2. In a printing press, the combination of a press operating shaft, a driving shaft, a power transmitting belt therebetween, a plurality of idler pulleys for controlling the 40 tautness of said belt; an operating lever carrying one of said pulleys and controlling the operation of the press, and a brake member associated with said operating lever adapted to be applied for stopping said 45 press.
3. In a printing press, the combination of a press operating shaft, a driving shaft, a power transmitting belt connecting same, a plurality of idler pulleys for controlling the 50 tautness of said belt, an operating lever for carrying one of said pulleys and for controlling the operation of the press, a brake member adapted to be applied for stopping the 55 operation of the press, and a cam member connected to said brake member and upon certain predetermined conditions being operatively connected to said operating lever for applying said brake member.
4. In a printing press, the combination of an operating lever for controlling the 60 operation of the press, a brake member adapted to be applied for stopping the operation of the press, a lever to which said 65 brake member is connected having a cam, said cam lever being engaged and operated directly by said control lever for applying the brake.
5. In a printing press, the combination of a press operating shaft, a driving shaft, a belt through which power is transmitted 70 from said driving shaft to said press operating shaft, means for controlling the tautness of said belt including a lever, and brake means disconnected from said lever under 75

normal running conditions adapted to stop the press.

6. In a printing press, the combination of a press operating shaft, a driving shaft, a belt for transmitting power between said 45 shafts, means for controlling the tautness of said belt including a lever, and a brake normally disconnected from said lever adapted to stop the press when said belt becomes ineffective for transmitting power from said driving shaft to said press operating shaft.

7. In a printing press, the combination of a press operating shaft, a driving shaft, a belt for transmitting power therebetween, and a plurality of cooperating idler pulleys 55 operatively associated with said belt whereby the tautness thereof is controlled.

8. In a printing press, the combination of a press operating shaft, a driving shaft, a belt for transmitting power therebetween, a plurality of cooperating idler pulleys 60 operatively associated with said belt whereby the tautness thereof is controlled, and brake means whereby the operation of said press is stopped upon a predetermined relative movement between said idler pulleys 65 causing said belt to become slack.

9. In a printing press, the combination of a press operating shaft, a driving shaft, pulleys mounted on said shafts, a belt connecting said pulleys for transmitting power 70 between said shafts, and a combined pulley and belt guard adapted to prevent a disengaging movement of the pulley on said driving shaft.

Signed at Chicago, Illinois, this 19th day of March, 1923.

BURT D. STEVENS.
